FIG. 1.

FIG. 2.

FIG. 3.

FIG. 4.

FIG. 5.

FIG. 6.

FIG. 7.

FIGURE 1 is a perspective view of a reading device for measuring rods or the like disclosing the lamp socket and objective, showing my new design;

FIG. 2 is a top plan view thereof, showing on top thereof of the reading window;

FIG. 3 is a perspective view thereof showing the lamp socket on top and the reading window at the side;

FIG. 4 is a perspective view thereof showing the lamp socket on the bottom and the objective projecting from one side face;

FIG. 5 is a front elevation thereof showing the objective projecting from a side face;

FIG. 6 is a perspective view thereof similar to the showing of FIG. 4, but showing the objective being set off by 90°; and

FIG. 7 is a front elevation thereof, similar to the showing in FIG. 5, but the objective being set off by 90°.

The essential features of the design reside in the portions shown in full lines.

I claim:

The ornamental design for a reading device for measuring rods or the like, as shown and described.
